INVENTOR

A. McL. Crawford.

UNITED STATES PATENT OFFICE.

ALEXANDER McL. CRAWFORD, OF CAMPBELL HALL, NEW YORK.

CONCEALED FLUSH HINGE.

SPECIFICATION forming part of Letters Patent No. 361,268, dated April 19, 1887.

Application filed January 12, 1887. Serial No. 224,090. (No model.)

To all whom it may concern:

Be it known that I, ALEXANDER McL. CRAWFORD, a citizen of the United States, residing at Campbell Hall, in the county of 5 Orange and State of New York, have invented a new and useful Concealed or Flush Hinge, of which the following is a specification.

The object of my new and improved hinge is to allow the edges of the hinged articles to which it is attached to fit snugly up to each other, and the surfaces thus connected to be perfectly smooth, the hinge being entirely hidden; and it is especially applicable to piano-lids, desk-tops, card-tables, and other articles having hinged parts in which polish and smoothness unobstructed by projecting hinges are desired. I attain these objects by the mechanism illustrated in the accompanying 20 drawings, in which—

Figure 1 represents a piano-lid, the dotted lines C C showing the position of my concealed or flush hinge when the piano-lid is closed. Fig. 2 is a section of my improved hinge, on 25 the line x x of Fig. 3, open. Fig. 3 is a section of my improved hinge, on the line y y of Fig. 2, closed. Fig. 4 is a section of my improved hinge, on the line y y of Fig. 2, open. Fig. 5 is a front view of my improved hinge 30 open, similar letters being used for similar parts throughout.

My concealed or flush hinge, which may be made of steel, iron, or any suitable metal or material, consists of three flat rectangular pieces, D D' g, Figs. 2, 3, and 4, of different 35 lengths, but of the same width and thickness, the ends of the piece g being square-dovetailed or box-dovetailed into one end of each of the pieces D and D', and held in place by 40 and turning upon pins f f' through the dovetailing, and to allow such turning it is necessary that the upper ends of the dovetailing of the pieces D D' g be slightly rounded off, while the under ends of the dovetailing of the 45 pieces must be square and true. The piece D is longer than either of the other two pieces, and is set into a case, C, and can be drawn outward and pushed inward in the case C to

a distance regulated by a slot, e, in each side of the case C and a pin, d, fixed in each side 50 of the piece D, working in the slot e. This slot e must correspond in length with the piece g, and the case C must be sufficiently long to allow the piece D to be drawn outward or pushed inward the length of the slot 55 e. The case C, with the inclosed piece D, is mortised into one portion, A, of the piano-lid or other article, and the piece D' is correspondingly mortised into the portion B of the piano-lid or other article, both pieces being 60 held in place by screws through the raised face-plates C C". The position of my hinge is then represented by Figs. 1 and 3, the piano-lid being closed.

To open the piano, the portion B of the 65 piano-lid is drawn forward the length of the slot e in the side of the case C, when the hinge will be in the position represented by Fig. 2. It is then only necessary to raise the portion B and lay it over upon the portion A, this being allowed by the rounding off of the upper ends of the dovetailing of D and D' g, the hinge then being in the position represented by Figs. 4 and 5. To close the piano-lid or other article, the operation is reversed. 75

Having fully described my invention, what I claim, and desire to protect by Letters Patent, is—

A hinge consisting of three flat rectangular pieces of the same width and thickness, but 80 of different lengths, the ends of one of these pieces being square-dovetailed or box-dovetailed into one end of each of the other two pieces, and held in place by and turning upon pins, the largest rectangular piece being set 85 into a case, and capable of being drawn outward and pushed inward in the case to a distance regulated by a slot in each side of the case, and a pin fixed in each side of the rectangular piece working in the slot, all substantially as set forth. 90

A. McL. CRAWFORD.
